BOARD SPLITTING MACHINE

Herbert H. Provence, Greenville, S. C.

Application May 5, 1950, Serial No. 160,211

6 Claims. (Cl. 164—51)

1

This invention relates to a board splitting machine and has relation more particularly to provide a machine for splitting the end portions of pulp board sheets to facilitate fabrication of cloth winding boards.

It is an object of the invention to provide a machine of this kind operating to deliver in required sequence the boards in required position to have the end portions thereof operated upon by a splitting means and to eject each board after the splitting operation.

The invention also has for an object to provide a machine of this kind including splitting knives mounted for movement one toward or from the other, together with means for shifting a sheet between the knives when separated and for ejecting a preceding sheet that may be between the knives and split, together with means for operating the knives and shifting means in required timed sequence.

A still further object of the invention is to provide a machine of this kind including a bed together with a magazine for holding a stack of sheets to one side of the bed and wherein further means are provided for intermittently shifting sheets from the stack into the bed.

An additional object of the invention is to provide a machine including a bed upon which a sheet to be split is positioned together with means for compressing the marginal portion or portions of the sheet to be split to facilitate the cutting operation.

The invention also embodies as an object to provide a machine of this kind including a bed with means for shifting a sheet to be split upon the bed and wherein further means are provided to clamp the sheet in working position upon the bed during the splitting operation, said last named means being ineffective after the splitting operation to allow the sheet to be ejected from the bed.

Furthermore it is an object of the invention to provide a machine of its kind including means for intermittently shifting sheets in position for the splitting operation and wherein means are provided for retarding such movement of the sheets to assure the same assuming proper position under the action of the shifting means for the sheets.

Again it is an object of the invention to provide a machine of this kind including a bed, a splitting means on the bed, means for intermittently shifting sheets on the bed into position for splitters, and a medium for frictionally engaging each sheet as it is shifted on the table

2

to prevent said shift being thrown out of splitting position by the shifting means.

The invention consists in the details of construction and in the combination and arrangement of the several parts of my improved Board Splitting Machine whereby certain advantages are attained, as will be hereinafter more fully set forth.

In order that my invention may be better understood, I will now proceed to describe the same with reference to the accompanying drawings, wherein:

Figure 1 is a view in top plan of a machine embodying the invention;

Figure 2 is a view in end elevation of the machine as comprised in Figure 1;

Figure 3 is a fragmentary detail sectional view taken substantially on the line 3—3 of Figure 2;

Figure 4 is an enlarged fragmentary view taken substantially on the line 4—4 of Figure 1;

Figure 5 is an enlarged fragmentary view taken substantially on the line 5—5 of Figure 1;

Figure 6 is a fragmentary detail sectional view taken substantially on the line 6—6 of Figure 4;

Figure 7 is a fragmentary detail sectional view taken substantially on the line 7—7 of Figure 1;

Figure 8 is a detail sectional view taken substantially on the line 8—8 of Figure 7;

Figure 9 is a view in perspective of a splitting blade unapplied;

Figure 10 is a fragmentary sectional view taken substantially on the line 10—10 of Figure 2;

Figure 11 is a fragmentary view in perspective of an end portion of a board illuminating the work done by the machine;

Figure 12 is a fragmentary detail view in end elevation of a corner of the machine illustrating the mounting for the cam operated rock arm;

Figure 13 is a fragmentary detail view partly in elevation and partly in section showing the intermediate bearing for the main shaft;

Figure 14 is a detail sectional view taken substantially on the line 14—14 of Figure 2;

Figure 15 is a detail sectional view taken substantially on the line 15—15 of Figure 2;

Figure 16 is a fragmentary detail view partly in section and partly in elevation of the cam operated pitman, and

Figure 17 is a view in top plan of one of the wedge plates unapplied.

In the embodiment of the invention as illustrated in the accompanying drawings, S denotes a skeletonized supporting structure including a corner uprights or posts 1, the lower portions 53 of the two of which at each side of the structure

S being connected by the interposed beam 2 rigidly secured thereto. Connecting the two beams 2 at one end portion of the structure S are the transversely disposed spaced parallel members 3 upon which is mounted an electric power unit P including a power take-off gear 4. This gear 4 meshes with a large gear 5 fixed to the power shaft 6 for the machine. Each end portion of the shaft 6 is operatively engaged with an underhung bearing 7 carried by an intermediate side beam 8 spaced above a side beam 2 and rigidly connected to the corner posts 1. The shaft 6 is also disposed through an upstanding bearing 9 carried by a beam 9a extending lengthwise of the frame and interposed between and rigidly secured to the cross members 10 connecting the corresponding end corner posts 1.

Between the gear wheel 5 and the intermediate bearing 9 is a circular cam disk 11 eccentrically mounted on the shaft 6 for rotation therewith. Snugly surrounding this disk 11 is a strap 12 carried by an extremity of a pitman 14. This pitman 14 is disposed inwardly of the structure S and the outer end portion thereof is operatively connected, as at 15, with an elongated rack bar 16 freely disposed through and supported by the end walls 17 of a box A for reciprocal movement. The stroke of the rack bar 16 is determined by the throw of the disk 11.

As herein embodied, the box A is substantially midway of the ends of the structure S and is rigidly carried by the channel beam 9a interposed between and rigidly connected to the end cross members 10.

Extending into the box A from the top thereof is the lower end portion of a vertical shaft 19 operatively engaged at its bottom portion with a bearing 20 on the bottom of the box A. The portion of the shaft 19 within the box A has rotating therewith a gear 21 which is constantly in mesh with the rack bar 16 so that the shaft 19 will be rotated to an extent determined by the stroke of the rack bar 16.

The upper end portion of the shaft 19 has rotating therewith a gear 22 interposed between 43 and constantly in mesh with the parallel rack bars 23 extending inwardly from and at opposite sides of the knife blocks 24 there being, of course, only one bar 23 for each of the blocks 24.

The blocks 24 are of desired dimensions and are slidably mounted on the parallel tracks 25 extending from one end of the structure S to the other end operatively supported upon the top end cross members 27 connecting to the top portions of the posts 1 at each end of the structure S.

In the present embodiment of the invention, the tracks 25 have their end portions resting from above upon the base members 28 mounted on the cross members 27 and held in position by the bolts 29 or otherwise as may be preferred. Each of these base members 28 has imposed thereon and extending therewith a block 30 snugly fitting between the tracks 25. The upper face of the block 30 has disposed transversely thereacross a channel 31 in which snugly and slidably engage an end portion of a bar 23. Each block 30 is held in position upon its associated base member 28 by the bolts 29.

The blocks 30 are held in position upon the base members 28 by the bolts 29 and the rack bars 23 are of such lengths to engage at all times with the blocks 30 at both ends of the structure S.

Each of the knife blocks 24 at each end thereof is provided thereacross with a depending flange 32 having close contact with the outer side face

5 of a track 25 and having its lower bottom edge face substantially flush with the bottom face of the track 25 which, as shown in the drawings, is rectangular in cross section. A plate 33 is bolted, as at 34, or otherwise detachably held to the bottom edge face of the flange 32 and closely underlies the adjacent track 25 so that the knife block is effectively maintained in working position.

10 Bolted, as at 35, or otherwise securely anchored to the outer corner portions of each knife block 24 are the upstanding brackets 36 in alignment lengthwise of the block and which supports a rock shaft 37. Fixed to the shaft 37 inwardly of but in close proximity to the brackets 36 are the parallel rock arms 38 connected for unitary swinging movement in the same direction by an interposed rigid member 39. These arms 38 rotatably support between their outer or free end portions a pressure roller 40 to engage the work from above at a selected distance beyond but at all times in close proximity to the cutting edge of the applied knife 41. Requisite pressure for the roller 40, when the machine is in operation, is created by the expansible member 42, herein disclosed as a coil spring, encircling the upper portion of an elongated headed shank 43 inserted from below through the inner marginal portion of the block 24 at substantially the longitudinal center thereof and freely through the member 39. The expansible member 42 is interposed between the top face of the member 39 and an enlargement or nut 44 threaded upon the upper extremity of the shank 43. The tension of the member or spring 42 may be regulated within certain limitations by adjustment of the member or nut 44 along the shank 43.

15 The knife 41, as herein disclosed, is rectangular in plan and of a length to extend entirely across the two tracks 25 carried by the supporting structure S. The knife 41 is also of material width and has its top surface a plane and disposed on an incline from the rear edge of the knife to the opposite edge or working portion. The working longitudinal marginal portion of the knife is beveled, as at b, to provide a sharp cutting edge c flush with the bottom plane face of the knife.

20 The knife 41 is placed from above on the inner marginal portion of the knife block 24 with the cutting edge c of the knife a desired distance outwardly from the adjacent longitudinal edge of the block 24. In the rear portion thereof the knife 41 is provided with the slots 41a through each of which passes a headed shank 45 inserted from below through the knife block 24. Threading upon the upper portion of the shank 45 is a clamping nut 46 to engage the knife 41 from above to hold the same in selective adjustment as allowed by the associated slot 41a and as determined by the desired placement of the cutting edge c with respect to the inner edge of the block 24.

25 The rear portion of the knife 41 is also provided with a suitably positioned slot 47 through which the shank 43 passes. Associated with the opposite end portions of the applied knife 41 are the wedge plates 48 which are interposed between the knife 41 and the knife block 24.

30 These wedge plates 48 provide means for adjusting the knives 41 by movement of the wedge plates in the required direction for the necessary distance, after which the nuts 46 are tightened to lock the knife 41 in selective vertical adjustment as may be required by the thickness of the sheet 49 to be slit by the knife 41. The headed shanks 45 are disposed through slots 41b disposed

longitudinally in the outer or rear portions of the wedge plates 48.

When the knife blocks 24 are in their outermost positions, the sheet 49 to be slit at its ends is delivered in required position upon the bed B mounted upon and supported by the central portions of the tracks 25. The sheet 49 is held in position on the bed B during the working operation thereon by the elongated pressure members 50 which in proper timing bear down upon the sheet 49 and hold the same in fixed position upon the bed B. The pressure members 50 are substantially in parallelism and extend across the bed B a distance substantially equal to the width of the sheet 49.

Each of the pressure members 50 at its end portions is provided with upstanding posts 51 which snugly but firmly engage within the downwardly opening sockets 52 in the elongated heads 53. See Figure 3. Threading into each of the heads 53 is a binding screw 53a for contact with the portion of the post 51 within the socket 52 of said headed member 53 so that the pressure member 50 may be held in selected adjustment with respect to the headed member 53 as the requirements of practice may dictate.

Each head 53 is provided with an upstanding post 54 which freely engages from below within a downwardly facing socket 55 of a bracket member M. This member M is carried by a pair of bars 56 extending the full length of the structure S. The extremities of each bar 56 rest upon the upper ends of the vertically disposed columns 57 held upon the extremities of a track 25 by the bolts 58 which extend up from the base members 28 and thread into the lower end portions of the columns 57. Each bar 56 is held upon the columns 57 by the bolts 58a passing down through the bar 56 and threading into the upper end portions of the columns 57.

As herein embodied each of the bars 56 is rectangular in cross section from end to end and the inner face of the body member 60 of each of the bracket members M is provided thereacross with a groove 61 which snugly receives the inner face portion of the associated bar 56. The body 60 at the top of each groove 61 is provided with an outstanding arm 62 perpendicular to the axis of the body 60 which arm has close contact from above with the associated bar 56. The outer end portion of each arm 62 carries a depending lug 63 having close contact with the outer edge face of the associated bar 56, and the outer end face of each lug 63 is slightly above the under face of the bar 56. Held to the outer end face of each lug 63 by the bolt 64 is a holding plate 65 underlying the adjacent bar 56 and clamping thereagainst by the bolt 64, whereby the bracket member may be held in selected position along the bar 56 as required by the length of the sheet 49.

The sockets 55 are each in the lower portion of a body member 60 of the bracket and extending through the upper portion of each body member 60 is a bore 60a through which passes an elongate stem 66 which is integral with and extends axially from the adjacent post 54. The sockets 55 are each of a depth considerably greater than the length of the post 54 therein and interposed between the inner or inserted end of each post 54 and the bottom of the socket 55 is an expansible member 67 of required tension and which is herein disclosed as a coil spring surrounding the stem 66.

The stems 66 have their upper or free end por-

tions connected by an interposed rigid tie member 68 so that the head members 53 will move in unison and in the same direction. The upper or free end portion of each of the stems 66 is disposed through an opening 69 in an end portion of the tie member 68 and threading upon the stem above and below the tie member 68 and bearing thereagainst are the holding nuts 70. By this means the tie member 68 may be adjusted as required lengthwise of the stems 66 and effectively held in selected adjustment.

In assembly, the bracket members M are side by side in arrangement and are provided with the inwardly disposed and aligned bosses 71 in the opposed end faces of which are rotatably received the outstanding trunnions 72 at the axial center of a flanged roller 73. Riding upon each roller 73 is a shifter bar 74 having its under or contacting surface straight and unobstructed while the upper portion of the bar 74 at its inner end portion is provided with an elongated recess 75 the opposite ends of which constitute cam shoulders 76. The recess 75 is of a length and of a depth to allow the associated pressure member 50 to have required clamping action on the sheet 49 during the cutting operation.

The shifter bar 74 moves with the knife block 24 and is positioned substantially midway of the tracks 25.

The upper portions of the brackets 36 are provided with the inwardly disposed and aligned arms 77 to which are bolted as at 78, or otherwise secured thereto, the extremities of a cross member 79. Rigid with the central portion of the cross member 79 is an upstanding pedestal 80 having in its top face a groove 81 in which seats the outer end portion of a bar 74. Extending upwardly from the pedestal 80 at opposite side of the groove 81 are the shanks 82 which extend up through the end portions of a holding member 83 contacting from above with a bar 74 and held in clamping action therein by the nuts 84 threaded upon the shanks outwardly of the holding member 83. This mounting of the bar 74 permits the same to be adjusted lengthwise to assure the desired positioning of the cam shoulders 76 with respect to the coacting bracket member M or more specially the top roller 74' rides upon the top surface of a shifter rod 74. This roller 74' is positioned below the central portion of the tie member 68 and is rotatably supported by and between the bearings 85 depending from the tie member 68. As the expansible members or springs 67 constantly urge the stems 66 downwardly, the top roller will at all times be in rolling contact from above with the bar 74 and thus assuring the desired downward movement of the pressure member 50 to have effective holding contact with the sheet 49 when required.

The bed B herein embodied comprises a relatively large central plate 86 bolted from below or otherwise detachably secured in a fixed position upon the tracks 25. The central portion of this plate 86 is provided therethrough with a relatively large circular opening 87 normally closed by a removable panel 88. The top surface of the panel 88 is substantially flush with the top surface of the plate 86 where the panel 88 is applied. The opening 87 is so positioned and is of a size to allow for the application and removal of the vertical shaft 19 and gear 22 when required.

In practice the sheets 49 are not always of the same length as such length is determined by the requirements of the consumer. To meet with

this condition the tracks 25 support thereon adjacent to the opposite ends of the plate 86 the supplemental plates 89, each of which is readily shiftable toward or from the plate 86 as the requirements of practice may demand. Each of these plates 89 is materially broad and underlying the end portions of the plates 89 and disposed transversely thereof is a clamping jaw 90 having a lip 91 engaging from below the adjacent track 25 whereby under the action of the bolt 92, the plate 89 may be securely held in selected adjustment with respect to the main plate 86.

The supplemental plates 89 in their upper surfaces are provided therealong with the grooves 93 in which are fitted the inner end portions of the elongated rigid arms 94 which extend a material distance beyond the one end of the bed B. The portions of the arms 94 within the grooves 93 are held to the plates 89 by the screws 95 or the like.

The arms 94 at desired distance outwardly from the plates 86 are provided with laterally and outwardly directed branch arms 96 preferably at right angles to the arms 94. The arms 96 are provided therealong with the spaced openings 97 to allow adjustable mounting thereon of upstanding stack retaining blades 98. The lower end of each blade 98 is provided with an outstanding foot 99 provided with an opening 100 to be brought into register with a selected opening 97 and through which registering openings a holding bolt 100a or the like is inserted to maintain the blade in desired position.

The outer extremities of the arms 94 are also provided lengthwise thereof with the spaced openings 101 to allow selected placing thereon of the upstanding retaining blades 102 for the outside of a stack of sheets 49 to be operated upon. The lower end portion of each of these blades 102 is provided with an outstanding foot 103 having openings 104 to be brought into register with the desired opening 101 and through which registering openings holding bolts 105 or the like are insertable.

The lugs 63 of the members M on the track 25 beyond which the arms 94 extend have rigidly secured thereto the upstanding plates 106 to which are bolted, as at 107, or otherwise secured thereto the upstanding blades 108 for retaining connection with the inner side of the pile or stack of sheets 49.

The blades 98, 102 and 108 coact to provide a magazine for the pile or stack of sheets 49 and the adjustable mounting of the blades 98 and 102 allow for compensation for sheets of differing lengths or widths.

The sheets 49 within the magazine are individually fed from the bottom of the stack into proper position upon the bed B and during which operation the knives 41 are at their outermost positions and the pressure members raised.

At suitable points inwardly of the grooves 93 the plate 86 is provided within its upper face with the relatively broad grooves 109 parallel to the grooves 93. Fitting within the outer side portions of the grooves 109 are end portions of the elongated arms 110 held to the plate 86 by the bolts 111 extending from below and threading into the arms 110. These arms 110 extend a material distance beyond the bed B from the same side as the arms 94 but herein shown as of greater length. The outer extremities of the arms 110 are connected by the interposed cross member 110a for maintaining the extended portions of the arms 110 in parallel relation.

The opposed faces of the extended portions of the arms 110 are provided along the upper part thereof with the rabbets 112 which provides tracks for the elongated feeding members 113. The inner portions of these arm members 113 slidably and snugly engage with the grooves 109 to one side of the applied inner portions of the arms 110.

The outer end extremities of the arms 113 are connected by an interposed head 114 which maintains said outer portion in desired parallel relation for effective engagement with the arms 110. This head 114 is welded to the inner or opposite faces of the arms 113 with its bottom face flush with the under surfaces of the arms 113.

Detachably held by bolts 115 or the like to the under face of the head 114 is a plate 116 which extends beyond the ends of the head and underlies the arms 110 whereby the arms 113 are maintained in working positions.

Positioned upon the outer portions of the arms 113 and extending therealong are the plates 117 of brass or other hard metal and which are detachably held in place by the screws 117a or the like. These plates 117 are of lengths greater than the width of the sheets 49 within the magazine with the inner end of the plates 117 in transverse alignment to provide shoulders 118 for contact with the lowermost sheet 49 of a stack or pile to shift such sheet in proper positions upon the bed B between the knife blocks 24. When the arms 113 are at the limit of their outward movement the shoulders 118 provided by the inner ends of the plates 117 are outwardly beyond the stack or pile within the magazine.

Pivotedly engaged from below, as at 119, to the central portion of the head 114 is an end portion of a rigid link 120 which is also pivotally connected as at 121 with a free end portion of a horizontally swinging sweep arm 122.

This sweep arm 122 extends inwardly of the structure from the end thereof adjacent to the shaft 6 and is fixed to the upper end portion of a vertically mounted shaft 123 which is held by the bearings 124 carried by a vertically disposed plate 125 rigid with the adjacent end arm member 27 and a second end cross member 126.

The lower part of the shaft 123 carries a laterally disposed arm 127 which engages with a continuous cam groove 128 in the periphery of a drum 129 fixed on the shaft 6 for rotation therewith. The throw of the cam groove 128 is such to rock the shaft 123 and more particularly the arm 122 to shift the arms 113 back and forth in required time sequence to deliver a sheet 49 in place upon the bed B for a slitting operation thereon.

At points spaced from the shoulders 118, a distance greater than the width of a sheet 49, the arms 113 are provided with the elongated through openings 113a at the forward portion of each of which is pivotally mounted the pin 130, and end portion of a dog 131. This dog is of a length to normally extend above the upper surface of the arm 113 for contact with a sheet 49 on the bed B after the sheet has been slit so that as the arms move inwardly to deliver a succeeding sheet upon the bed the previously slit sheet will be ejected from the opposite side of the bed.

The normal position of the dog is determined by contact of the dog 131 with the rear end wall of the opening 113a and such position is maintained by a depending tail piece 132 integral with and depending from the lower or pivoted end

of the dog 131. This tail piece 132 is of a weight greater than that of the dog 131 proper.

The tail piece 132 is of a length to extend below the arm 113 when the dog 131 is in its normal position. To accommodate the outer portion of the tail piece, the bottom wall of the groove 109 below the arm 113 is provided therewith a supplemental groove 133 of proper depth.

Whenever desired, a dirt shield may be used. In the present instance such a shield 134 is provided along the upper portion of the supporting structure at the discharge or delivery side thereof. Carried by this shield 134 and extending outwardly and downwardly therefrom are chute fingers 135 upon which a sheet 49 is initially received upon ejection from the bed B.

It is to be noted that when the arms 113 are at the limit of their feeding movement with respect to the bed B the outer portions of the plates 117 are under the stack or pile within the magazine to assure uninterrupted return on outward movement of the arms 113.

It is also necessary that the plates 117 be movable as in practice such plates are subject to great wear and need frequently to be replaced although of brass or other hard metal.

It is important to provide means to retard the power movements of a sheet 49 as it is forced on the bed B by the arm 13 and it is preferred that a friction means be employed. As shown in the accompanying drawings this is obtained by suspending from the tracks 25 a head 136 extending across the bed B and of a length approximately the width of a sheet 49. Depending from the head are the bristles 137 of a length to closely engage the sheet from above as the sheet 49 moves onto the bed B.

In the present embodiment of the invention the head 136 is maintained in position by the elongated hanger stems 138 which are rigidly secured to the end portions of the head 136 and extend up through the tracks 25. Threaded on each stem 138 are the binding nuts 139 above and below the associated track 25 for close contact with the track to lock the stem 138 in accordance with the desired adjustment of the bristles 137 of the head 138 with respect to the bed B.

While the machine as herein comprised is particularly adapted for use in splitting the ends of the sheets 49, Figure 11, for the production of cloth winding boards such as comprised in Patent No. 1,977,144 dated October 16, 1934, the invention is not to be limited to this particular use.

In practice a stack or pile of sheets 49 is placed within the magazine afforded by the blades 98, 102 and 108. Upon closing the circuit for the power unit P required reciprocation will be effected for the feeding members 113 together with the reciprocation in required timed sequence of the knife blocks 24, said blocks 24 being at the limit of their outward movements when the members 113 are at the limit of their inward or feeding movements.

As the feeding members 113 move inwardly from their outermost positions the shoulders 118 provided by the plates 117 on the members or arms 113 will contact the bottom sheet 49 of the stack or pile within the magazine and shift said sheet in proper position upon the bed B and during which shifting movement the pressure members 50 are maintained in their raised or ineffective position.

As the members or arms 113 move inwardly to shift a sheet 49 upon the bed B, the dogs 131 will contact a sheet 49 that may be on the bed and shift the same transversely across the bed B and eject the sheet beyond the side of the bed B remote from the delivery side for the sheets. As the members or arms are retracted or moved outwardly the dogs 131 will readily swing upon contact with the sheet just delivered upon the bed B to readily pass under the sheet. It is also to be pointed out that as a sheet 49 is delivered upon the bed B, the bristles 137 will have sufficient frictional contact from above upon the sheet 49 to assure the sheet immediately coming to a stand-still when the arms or members 113 reach the limit of their inward or shifting movement. The bristles 137 are, however, sufficiently flexible or yieldable to allow a sheet 49 to be forced therebeneath.

As the arms or members 113 retract or move outwardly, the knife blocks 24 will be caused to simultaneously move inwardly toward the ends of the sheet 49 on the bed and for a distance sufficient to cause the knives 41 to split the end portions of the sheet 49. Shortly after the knife blocks start their inward movements the recesses 75 in the bars 74 allow the pressure members 50 to bear down from above upon the sheet 49 on the bed B and effectively hold said sheet to allow for the splitting cutting action by the knives 41. After the knife blocks 24 have been retracted or moved outwardly a distance to free the knives 41 from the sheet 49, the pressure members will be raised under the action of the inner cam members 76 of the bars 74.

As the blocks 24 approach the ends of the sheet 49 on the bed B and before the knives 41 enter the end portions of the sheet 49, said end portions of the sheet 49 are compressed by the rollers 40 so that the said end portions of the sheet 49 will be in the best possible position to assure the desired splitting operation.

From the foregoing description it is thought to be obvious that a board splitting machine constructed in accordance with my invention is particularly well adapted for use by reason of the convenience and facility with which it may be assembled and operated.

I claim:

1. A sheet slitting machine of the character described including a bed upon which a sheet is laid, a knife, a carrying block for the knife, means supporting the block for rectilinear movement relative to a side of the bed for effecting the splitting of an edge of the sheet by the knife when the block is moved toward the bed, a pressure bar disposed across the bed, means supporting said bar for vertical movement to engage and hold the sheet to the bed when moved downwardly, means for constantly urging the bar down into sheet holding position, means for reciprocally moving the block, and means operatively connected to the block and the bar for effecting movement of the bar away from the bed against the action of said urging means to free the bar from the sheet when the block is moved away from the bed and sheet.

2. A sheet slitting machine of the character described including a bed upon which a sheet is laid, a block, means supporting the block for movement toward or from a side of the bed and an edge of a sheet thereon, a knife carried by the block and having a cutting edge projecting toward the bed to enter an adjacent edge of a sheet upon the bed between the top and bottom

11

faces of the sheet when the block is moved toward the bed, a pressure bar disposed above and across the bed adjacent to the said side thereof, means supporting the bar for up and down movement, the bar when moved down engaging the sheet on the bed to hold the sheet, means constantly urging the bar toward the bed for clamping action, a shift bar operatively supported by and movable with the block and disposed in a plane above the bed, and coacting means between the clamping bar and the shift bar for raising the clamping bar upon movement of the block away from the bed and for permitting the bar urging means to move the clamping bar into holding engagement with the sheet during the cutting operation of the knife.

3. A sheet slitting machine of the character described including a bed upon which a sheet is laid, a block, means supporting the block for movement toward or from the adjacent side of the bed and an edge of a sheet thereon, a knife carried by the block and projecting toward the bed to enter an edge of the sheet upon the bed between the flat surfaces of the sheet as the block moves toward the bed, a bracket carried by and movable with the block, a bar secured to the bracket and extending toward and over the bed, said bar having a longitudinal recess therein having end cam shoulders, a clamping bar disposed across the bed to engage a sheet to hold the latter to the bed, guide brackets supported above the bed at opposite sides thereof, elongate stems freely disposed through the guide brackets for vertical movement, means operatively connecting the lower portions of the stems to the clamping bar, means for constantly urging the stems and clamping bar toward the bed to maintain the clamping bar in sheet holding position, a tie member connecting the upper portions of the stems and movable therewith, an underhung roller carried by the tie member, a second roller positioned between and rotatably supported by the guide brackets, said rollers being spaced one above the other, said recessed bar being disposed between and constantly engaged by the rollers, said bar extending in the same general direction as the path of travel of the block, the recessed surface of the bar being engaged by the roller of the tie member, the clamping bar being in sheet holding position when the roller of the tie member is within the recess and held out of such position when the roller of the tie member is elevated at either end of the recess by engagement with said cam ends.

4. Apparatus for splitting an edge of a fiber sheet, comprising a pair of elongate guide tracks, a sheet supporting bed disposed above and across the tracks, a knife block disposed horizontally across the tracks and slidably connected thereto for rectilinear movement relative to the bed, an elongate knife secured to and across said block and having a cutting edge projecting beyond the

12

block toward the bed in a horizontal plane, bracket members carried by the block, a clamp means supported by and between the bracket members, a second bracket supported above the bed and tracks across the space between the tracks, a pair of spaced stems vertically supported above the bed by the second bracket for up and down movement in a vertical plane in front of the maximum advance position of the knife edge, spring means constantly urging downward movement of the stems, an elongate shift bar secured at one end to said clamp means and having rectilinear movement with said block, spaced cam elements carried by said shift bar, said shift bar extending across the second bracket, coupling means between said stems, a follower element carried by the coupling means for engagement by said cam elements to lift the stems against the action of said springs, a pressure bar connected with the lower ends of the stems for engaging a sheet adjacent to said maximum advance position of the knife edge to hold the sheet on the bed, and means for reciprocably moving the knife blocks on the tracks.

5. Apparatus of the character stated in claim 4, wherein said knife has its cutting edge disposed to extend at a forward and downward inclination relative to the top surface of the supporting block, and a means for changing said inclination comprising a tapered wedge member interposed between the back portion of the knife and the block.

6. Apparatus of the character stated in claim 4, with a rock shaft connected between said bracket members, a pair of arms carried by and extending forwardly from the shaft, a pressure roller supported between the forward ends of the arms in advance of the cutting edge of the knife, and spring means operatively coupled between the arms and block and urging the arms and roller downward, said roller being positioned between the knife edge and the pressure bar when the knife has completed its movement toward the bed.
